UNITED STATES PATENT OFFICE

145,139

DESIGN FOR A UTILITY TRUCK

George H. Lowerre, Balboa Island, Calif.

Application December 14, 1944, Serial No. 116,894

Term of patent 3½ years

(Cl. D14—3)

To all whom it may concern:

Be it known that I, George H. Lowerre, a citizen of the United States of America, residing at Balboa Island, county of Orange, and State of California, have invented a new, original, and ornamental Design for a Utility Truck, of which the following is a specification, reference being had to the accompanying drawing, forming a part thereof wherein:

Figure 1 is a perspective view of a utility truck showing a new design.

Figure 2 is an opposite perspective view.

The side of the device opposite that shown by the drawing figures is the same as illustrated.

I claim:

The ornamental design for a utility truck, as shown.

GEORGE H. LOWERRE.
